6 Claims. (Cl. 75—67)

1

The present invention relates generally to a method for cooling gaseous media by interchange of heat with cooling gases, and more particularly for condensing vapors, such as metallic vapors which are mixed with gases that have a tendency to react chemically with the said vapors. However the invention will be described, for purposes of illustration, with particular reference to the manufacture of magnesium from magnesia or magnesia-containing ores while using a carbonaceous material as the reducing agent.

In the thermal reduction of magnesium oxide with carbon the reaction proceeds according to the equation $MgO + C \rightleftharpoons Mg + CO$ with production of a mixture of magnesium vapor and carbon monoxide. At a sufficiently high temperature the reversion of the reaction from right to left is efficiently repressed, but if the reaction products are allowed to cool gradually the reverse reaction progresses so rapidly that the starting materials MgO and C are reformed substantially completely and no material amount of magnesium is recovered.

It is now well known that the reversion of the reaction can be minimized by keeping the mixture of magnesium vapor and carbon monoxide up to the point at which it leaves the furnace at such a high temperature that the reaction proceeds practically to the right, and then suddenly cooling (shock-chilling) the mixture at this very point, by the injection of fine jets of a non-oxidizing gas, down to a temperature at which under the dilution conditions existing magnesium and carbon monoxide are stable in the presence of each other. Since that temperature lies below the solidification point of metallic magnesium, the metal is condensed in this way in the form of a finely divided dust. Usually shock-chilling is effected by introducing into the escaping mixture of highly heated reduction products a cooled gas, which is inert or substantially inert to magnesium, such as hydrogen or a noble gas, particularly helium, or in industrial hydrocarbon, or natural mixtures of hydrocarbons such as natural gas.

As large quantities of the chilling gas are required in commercial operations of any appreciable scale, with coolants other than natural gas, it is unavoidable to return the coolant in cycles, and this can not be done without removal of carbon monoxide before recirculation. However, it is already known that it is not necessary to reclaim the entire volume of gas employed for chilling, but suffices to remove an amount of carbon monoxide corresponding to the increment due to

2

CO formation in the reduction stage. For that purpose it has been proposed to divide the gas mixture left behind after separation from the powdery condensate, into two portions, of which 5 a smaller one is detached for reuse in an unchanged condition, whereas the other portion is subjected to a treatment capable of reducing the carbon monoxide content therein; eventually these two fractions are united to lead back into the circuit the gas mixture thus obtained (cf. U. S. Patent No. 2,200,772).

It is a particular object of the invention to provide a method in which a portion of the chilling gas used is recirculated in a cooled but 15 otherwise unchanged condition, and a quantity of fresh gas or recirculated gas substantially freed from carbon monoxide, which is referred to as "make-up" gas in the following, is added to the vapor-gas mixture to be chilled at a point and 20 in a manner to obtain the greatest shock-chilling efficiency.

Other objects and advantages of the invention will become apparent from the following description taken in connection with the accompanying 25 drawings.

To accomplish these objects the invention essentially contemplates that the recirculated gas and the make-up gas are maintained separately and separately intermingled with the gas vapor mixture to be chilled while introducing the make-up gas into the flow of the hot reduction products to be chilled at a zone in advance of the introduction of the gas that is recirculated in a cooled but otherwise unchanged condition. The 30 recirculated gas then enters the flow to supply the balance of the required volume and supplement the cooling effect of the make-up gas.

Natural gas which is available in large quantities and inexpensive enough to be subsequently 35 burned as a fuel, is most attractive for use as a chilling agent in the service of the carbothermic method of producing magnesium. For these reasons the present method, too, is particularly adapted to be applied in connection with chilling 40 the vapor-gas mixture escaping from the reduction furnace by means of natural gas, of which a portion is reused in a cooled but otherwise unchanged condition with the addition of fresh gas, whereas the other portion passes off to be led into a fuel system. In case of using gases 45 other than natural gas as coolants, the portion introduced as fresh gas in the case of natural gas has to consist of recirculated coolant which had previously been subjected to a treatment for 50 eliminating or materially reducing the CO con-

tent thereof, and which has been cooled down to an adequately lower temperature and elevated at an adequately higher pressure. Yet in doing so, the make-up gas may also consist of, or contain, a portion of fresh gas, in which case an amount of gas escaping from the reduction furnace equivalent to the proportion of fresh gas introduced would have to be rejected.

Thus the make-up gas is either low in, or free from, carbon monoxide and also in a cooler state and available under higher pressures and hence a more efficient chilling agent than the recirculated gas. Consequently in this way the initial impingement and intermingling of chilling gas and reduction products to be cooled takes place between the hottest vapors and the coldest gas under highest pressure. The rate of back reaction is evidently greatest at elevated temperatures which are only slightly lower than the equilibrium temperatures for the operating conditions of the particular partial pressures involved. Therefore the lower the percentage of CO in the coolant initially introduced and the more rapid the initial cooling rate, the more effective the shock-chilling operation. Whether the make-up gas consists of fresh gas or of appropriately reclaimed recirculated gas, all in all this arrangement results in a saving in volume as well as in pressure and cooling of the total quantity of gas necessary to gain the desired end.

No matter what gas is used, it must enter the chilling cone at a temperature sufficiently below the final shock-chilling temperature, that is, approximately at 200° C., to effect a cooling without resorting to circulating impractical quantities of gas. The proportions of chilling gas circulated and make-up gas introduced on the one hand, and the entering temperatures on the other, have to be balanced against each other to arrive at favorable economical working conditions. The pressure at which the make-up gas and the recirculated gas, respectively, are elevated is likewise a function of economics to achieve rapid mixing in a limited distance from the outlet port without resorting to excessive horsepower for compression. It is obvious that this, too, ties in with the quantities of gas to be circulated which on their part are a function of the temperature.

An apparatus which may be used according to the invention for carrying out the process described is illustrated by way of example in the accompanying drawings.

Fig. 1 is a longitudinal sectional view taken through a chilling device which embodies the present invention.

Fig. 2 is an enlarged fragmentary detail in section of a part of the inner end of the device shown in Fig. 1.

Fig. 3 is an elevational view, with parts in section, of the device shown in Fig. 1, as viewed from the right hand end, and

Fig. 4 is a fragmentary isometric view of a portion of the device shown in Fig. 1, the outer shell part thereof being removed to disclose the arrangement of parts hidden thereby.

The apparatus shown comprises an inner shell 10 in the shape of a truncated cone, which is connected at its inner end, that is the end in juxtaposition to the outlet opening in the furnace wall, with a perforated or slotted frusto-conical member 11 which serves as a nozzle plate for the admission of the chilling gas, its slots acting in the manner of nozzles in directing the gas to the interior of the frusto-conically shaped member 10. While the nozzle openings herein shown are in the

form of slots milled through the nozzle plate, they may be of any desired shape consistent with their function which is to admit chilling gas to the interior of the shell 10 so as to cause the gas to mix violently with the hot vapors passing therethrough. A plurality of circular orifices may be preferable in the zone where the high pressure make-up gas is introduced, while economically milled slots appear to be entirely adequate for the introduction of the recirculated gases at relatively lower pressures, which latter may contain a small amount of solid particles owing to imperfect or damaged dust filters. It appears that dust that collects at the edges of the openings tends to break away and free itself more readily from the long edges of the slots than it does from circular openings.

The members 10 and 11 are surrounded by a frusto-conical outer shell member 12 spaced from the member 10 to form a channel or passage of conical contour through which gas may be delivered to the nozzle plate 11. The members 10, 11, and 12 are connected together by means presently to be described to form a unit which is insertable in a suitable recess in the wall 13 of the furnace so that the inner end of the frusto-conically shaped unit communicates with the interior of the furnace crucible while the outer end thereof projects to a point outside the wall of the furnace where it is connected with a dust collecting chamber or other dust collecting and separating device.

As shown in Figure 1, the outlet of the wall 13 of the furnace crucible is lined with an annular replaceable insert 14 of graphite or other material resistant to the erosive effects of the hot reduction products escaping from the furnace. The furnace usually has an outer metallic shell 5 spaced from the crucible, and the space between the shell and the crucible is filled with a heat insulating material 6 which may be lamp black or other finely divided carbonaceous substance. In the present instance an opening for the reception of the chilling cone is defined through the furnace insulating material by a double walled frusto-conical member 15 which is cooled by a liquid coolant such as oil for its own protection and also for the protection of the chilling cone against the furnace heat. A connection is made between the member 15 and the furnace wall 5 by means of a pair of flanges 7, one carried by the furnace wall, and the other by the member 15. The inner end of the member 15 is spaced at short distance from the outer wall of the furnace and the space is sealed by packing 8 of asbestos rope or other material capable of preventing leakage of the finely divided insulating material to the interior of the space occupied by the chilling cone. This loose connection between the cone 15 and the furnace crucible permits the crucible to expand both radially and vertically without contacting or distorting the cone. The inner end of the member 15 is sufficiently large in diameter to permit removal and replacement of the graphite insert 14 which may become eroded or otherwise defective after long-continued service due to the temperature and nature of the vapor which passes through it.

The cooling fluid may be introduced to the interior of the member 15 through an annular manifold pipe 16 adjacent to its outer end and communicated to its inner end through a plurality of longitudinally extending pipes, one of which is shown at 17 in Figs. 1 and 2. The cooling fluid enters the manifold 16 through a supply pipe 18

and is conducted through the pipes 17 to the innermost end of the space through which it is circulated, then flows back around the outside of the pipes 17 and passes out through a discharge pipe 19. The inner ends of the pipes 17 are preferably cut at an angle, as illustrated, to cause the cooling fluid delivered through the pipes to sweep the interior of the space to be cooled with a sort of circular motion and thus maintain a constant movement of the coolant against the surfaces as it flows back toward the discharge pipe 19. The outer end of the double walled member 15 is provided with a flange 20. A gas tight connection between this flange and a manifold housing 21, which is carried by the outer shell 12 of the chilling cone, is formed by an expansion plate 9 which is in the form of a flexible metal ribbed annulus fastened at both edges by cap screws and suitable gaskets or the like (not shown) for forming a perfect seal. This expansion plate 9 provides sufficient flexibility to absorb movement due to expansion and contraction between the member 15 and the enclosed chilling cone. The inner end of the chilling cone assembly is, as will presently appear, also spaced slightly from the crucible to permit movement in all directions resulting from expansion and contraction.

The chilling gas is delivered to the outside of the outermost end of the nozzle plate 11 through the manifold 21 which surrounds the outer shell 12 adjacent to its right hand end and communicates with the space between the shells 10 and 12. To introduce the portions of the recirculated gas and make-up gas separately and at different points in the flow of the gaseous reduction products to be chilled, the supply manifold 21 through which the chilling gas is introduced is divided by an annular wall 22 to form an outer manifold 23 for make-up gas, and an inner manifold 24 for recirculated gas. As shown in Fig. 3 a supply conduit 25 for recirculated gas extends through the outer manifold and communicates with the inner manifold 24, while a supply conduit 26 for make-up gas communicates directly with the outer manifold. The recirculated gas entering through the manifold 24 flows inwardly between the conical shells 10 and 12 in cooling contact with the exterior of shell 10 and then passes through the slots of the nozzle plate 11 into the interior of the chilling cone where it mingles with the hot furnace products. On the other hand, the make-up gas which enters the manifold 23 is communicated by pipes such as indicated at 27, to the left hand end of the space between the members 10 and 12 and through a wall 28 which forms the inner boundary of the main portion of this space and which separates the inner portion of the nozzle member 11 from the outer portion thereof. Thus the make-up gas is supplied to a small annular chamber 29 and escapes through openings in the inner end of the nozzle plate 11 to mix violently with, and chill, the furnace vapors immediately as they emerge from the crucible at a point in advance of the introduction of the recirculated gas. The inner portion of the chamber 29 is defined by a double walled flange 30 the interior of which provides a casing for the circulation of a cooling fluid and thus protects the entire inner face of the chilling cone from the heat of the furnace. Cooling fluid is supplied to the protecting flange 30 through a plurality of small pipes 31 which communicate with an annular manifold pipe 32 disposed within an exhaust manifold chamber 33 that is formed by a wall 34 defining the right hand end of the space between

the shells 10 and 12. The cooling fluid is furnished to the supply manifold through a pipe 35 and flows from the manifold through the pipes 31, which penetrate the wall 34 and also the wall 28 and terminate, as best shown in Fig. 2, adjacent the innermost end of flange 30 where they are preferably cut diagonally to induce a circular or sweeping flow within the flange. This coolant discharges through pipes 36 one of which is shown in the lower part of Fig. 1 and which, as also illustrated in Fig. 4 communicate with the interior of the flange 30 and with the exhaust chamber 33, from which the fluid escapes through a discharge pipe 37. It is an advantage of the arrangement herein shown that the chilling gas enters through what may be likened to a very large conduit so that a lower initial gas pressure will suffice to deliver a large volume of gas and produce a high nozzle velocity at the nozzle plate 11. While the space between the members 10 and 11 includes the make-up fluid pipes 27 and the cooling gas supply and discharge pipes 31 and 36, all as illustrated in Fig. 4 of the drawings, there still remains an unusually large area for the transmission of recirculated gas to the nozzle.

In Fig. 4 the relative positions assumed by the pipes 21, 31, and 36 are indicated and the pipes 31 and 36 are shown as provided with expansion bends 40 which serve to absorb any distortion resulting from variations in temperature. Such a bend is preferably eliminated from the pipe 21, the inner end of which is loosely fitted in a suitable perforation in the wall 28 so that it is free to move linearly when subjected to temperatures different from that of the parent member. The sliding fit of the pipe 27 where it pierces the wall 28 may permit leakage of a small quantity of make-up gas through this wall, but this leakage is of no consequence because the escaping gas simply enters the area occupied by the recirculated chilling gas.

Fig. 4 also illustrates one of a plurality of spacer plates 41 which may be disposed between the inner and outer shells 10 to brace and maintain them in their concentric positions. The spacer plates and pipe occupying this area may be as numerous as required by the functions which they perform and yet leave the space substantially unobstructed for the passage of a very large volume of a chilling gas which serves as a coolant in contact with the inner shell 10 and which eventually enters through the nozzles the interior of the cone where it chills the furnace vapors by direct contact.

The form of the apparatus herein disclosed permits the use of scrapers for maintaining the inside surfaces of the conically shaped chilling chamber free of undesirable deposits. Likewise, spray devices may be employed for wetting and rendering inactive pyrophoric materials within the cone prior to its being opened to the atmosphere for inspection and repair. Such scrapers and spray devices are well known to the art (cf. U. S. Patent No. 2,109,841). Besides their illustration herein is unnecessary to an understanding of the present invention.

The term "make-up" gas is used in the following claims to include not only fresh gas, but also reclaimed gas which is substantially free from, or low in, carbon monoxide.

This application is a division of my copending application, Serial Number 585,884, filed March 31, 1945.

I claim:

1. In the process of making metallic magnesium in which a mixture of magnesium vapor and carbon monoxide gas is chilled suddenly, by intermingling a chilling gas therewith, from a high temperature at which the reaction

proceeds practically from left to right, to a low temperature at which reoxidation of the magnesium formed by the carbon monoxide present is minimized, the steps of recirculating some of the chilling gas employed and continuously adding a quantity of make-up gas, the said make-up gas being introduced into the flow of the vapor-gas mixture to be chilled in a zone preceding the zone of introduction of the recirculated gas.

2. In the process of making metallic magnesium in which a mixture of magnesium vapor and carbon monoxide gas is chilled suddenly, by intermingling a chilling gas therewith, from a high temperature at which the reaction

proceeds practically from left to right, to a low temperature at which reoxidation of the magnesium formed by the carbon monoxide present is minimized, the steps of recirculating some of the chilling gas employed while passing it in cooling contact with a casing which confines the vapor-gas mixture to be chilled to a zone where it is caused to escape into the interior of said casing and to mingle with the hot vapor-gas mixture,

and separately adding a supply of make-up gas by introducing the same to the flow of the vapor-gas mixture to be chilled in a zone preceding that where the recirculated gas is added.

3. In the process of cooling gaseous media comprising magnesium and carbon monoxide by interchange of heat with cooling gases, that combination of steps which comprises separating a portion of the exhaust chilling gas, recirculating a stream of the separated gas in a cooled but otherwise unchanged condition into the medium to be cooled, and separately adding a quantity of make-up gas cooled to a lower temperature and elevated at a higher pressure than is the recirculated gas, by introducing the said make-up gas into the flow of the medium to be cooled in a zone preceding that of the introduction of the recirculated gas.

4. The process of claim 1, wherein the chilling gas is natural gas.

5. The process of claim 1, wherein the chilling gas is hydrogen.

6. The process of claim 1, wherein the chilling gas is a noble gas.

DONALD A. RHOADES.
